UNITED STATES PATENT OFFICE.

ALFRED WHETSTONE, OF MOUNT CARMEL, PENNSYLVANIA.

WINDOW OR DOOR SCREEN.

1,268,653.

Specification of Letters Patent. Patented June 4, 1918.

Application filed July 12, 1917. Serial No. 180,130.

To all whom it may concern:

Be it known that I, ALFRED WHETSTONE, a citizen of the United States, residing at Mount Carmel, in the county of Northumberland and State of Pennsylvania, have invented certain new and useful Improvements in Window or Door Screens; and I do hereby declare the following to be a full, clear, and exact description of the invention, such as will enable others skilled in the art to which it appertains to make and use the same.

The purpose of this invention is to provide a construction for doors and windows that will permit flies and other winged insects to pass out of the room, but will effectively prevent them from reentering the room through the exit opening in the screen.

With this and other objects in view, the invention consists in the novel construction, combination and arrangement of parts as will be hereinafter specifically described, claimed and illustrated in the accompanying drawings, in which:

25 Figure 1 represents an elevation of the inside of the window screen,

Fig. 2 represents a horizontal sectional view on the line 2—2 of Fig. 1,

Fig. 3 represents a vertical sectional view 30 on the line 3—3 of Fig. 1,

Fig. 4 represents a fragmentary perspective view of the lower end of the window screen,

Fig. 5 represents an enlarged fragmentary 35 perspective view of the medial portion of the screen, illustrating one of the exit openings,

Fig. 6 represents a fragmentary elevation 40 of the outside of the screen,

Fig. 7 represents a fragmentary side elevation of a modified form of screen, and

Fig. 8 represents a detail sectional view 45 through the modified structure.

Referring to the drawings in detail, 50 wherein similar reference numerals designate corresponding parts throughout the several views, the numeral 5 indicates a substantially rectangular frame, carrying laterally projecting and angular flanges 6, 55 constituting guides for the movable frame 7 which is slidably supported therein and is retained in engagement with the frame 5 by the angular edges of the flanges 6.

Upper and lower screen sections 8 and 9 55 are secured to the outside of the frame 5

by removable strips 10, and the adjacent edges of the screen sections 8 and 9 are arranged in spaced relation to provide the exit opening 11. Several of the horizontal wires of the lower screen section 9 are removed at the upper edge thereof and the vertical wires are turned outwardly at their upper terminals, as indicated at 12, to provide guards designed to prevent the entrance of flies into the room in which the screen is located.

A guard plate 13 constructed of imperforate sheet metal or screen is secured to the inner surface of the outer frame 5 by screws, or equivalent means 14, and is arranged directly behind or inwardly of the exit opening 11. The upper edge 15 of the plate is extended outwardly between the vertical members of the frame 5 and is bent to define a U-shaped clamping member 16, in which the lower edge of the upper screen section 8 is firmly clamped. As clearly shown in Figs. 3 and 5, the clamping member 16 carried by the plate 13 is arranged in spaced relation to the outwardly directed terminal 12 of the wires of the lower screen section 9 so as not to close the exit opening 11.

The horizontal wires at the extreme upper end of the upper screen section 8 are also removed and the upper terminals of the vertical wires of the screen section are directly outwardly, as indicated at 17, to prevent flies from entering through the exit opening 18 in the upper part of the frame 5. An imperforate plate 19 is secured to the inner surface of the frame 5 and connects with the upper horizontal member of said frame, as shown in Fig. 3.

The outer surface of the inner frame 7 is also provided with strips 20, which secure the screen section 21 to the outer face thereof. The upper edge of the screen section 21 terminates in spaced relation to the upper horizontal member of the frame 5 to provide the exit opening 22, and an imperforate plate 23 is secured to the inner surface of the frame 7 directly behind or inwardly of the opening 22, and the upper terminals of the screen section 21 are preferably directed outwardly toward the frame 5 to insure against the entrance of the flies through the exit opening 22, in the direction of the interior of the room in which the screen is arranged. The upper edge of the screen section 21 is also arranged in spaced

relation to the plate 19 carried by the frame 5, so that when the two frames 5 and 7 are arranged one inwardly of the other a circuitous passage between the openings 22 and 18 for the exit of the flies is provided.

Each of the plates 13, 19 and 23 is connected with its respective screen section by a spacing element 24, having a tapered lower terminal.

10 The outer surfaces, or those surfaces of the several plates which are presented to the outside of the room, are preferably dark in color so as not to attract the flies or other insects to the exit openings.

15 In the modified structure illustrated in Figs. 7 and 8, the screen section 25 is provided with a series of spaced slits constituting exit openings 26. The terminals of the horizontal and vertical screen wires, 20 at the edges of the openings, are turned outwardly to provide guards 27.

What I claim is:

1. A screen structure including a frame, a screen section secured in the frame, said screen structure having an exit opening therein, the screen wires at the edge of the opening being bent laterally to provide guards, and a plate secured to the frame at the side of the opening opposite the

guards and having the surface adjacent the opening darkened.

2. A screen structure including a frame, screen sections secured to the frame and arranged in spaced relation to provide an exit opening, a plate secured to the frame laterally of the exit opening and provided with an angular edge directed outwardly toward the screen sections, and a clamping member carried by the forwardly directed edge of the plate receiving the lower edge of the upper screen section.

3. A screen structure including a frame, supporting flanges carried by the frame, a relatively movable frame supported in the flanges, screen sections secured in the frames and having exit openings in the upper portions thereof, and plates secured to the upper portions of the two frames inwardly of the exit openings and arranged in spaced relation to the screen sections to provide a circuitous passage between the exit openings.

In testimony whereof I affix my signature in presence of two witnesses.

ALFRED WHETSTONE.
